UNITED STATES PATENT OFFICE.

JOHN W. GRAHAM, OF HINTON, WEST VIRGINIA.

TYPOGRAPHICAL MACHINE.

1,148,086.

Specification of Letters Patent. Patented July 27, 1915.

Application filed October 10, 1914. Serial No. 866,069.

To all whom it may concern:

Be it known that I, JOHN W. GRAHAM, a citizen of the United States, residing at Hinton, in the county of Summers and State of West Virginia, have invented new and useful Improvements in Typographical Machines, of which the following is a specification.

This invention relates to typographical machines such as linotype machines of the kind disclosed in the patent to O. Mergenthaler, No. 436,532, wherein circulating matrices are released from magazines in the order in which their characters are to appear in print and then assembled in line together with expanding spacers, the composed line being transferred to the face of a mold, the latter being filled with molten metal to form a slug or linotype against which they started.

The object of the present invention is to provide in connection with a suitable supporting frame, a rack in which any desired number of matrix magazines may be placed and removed or interchanged at will, the said rack being shiftable up and down to bring the magazines into proper alinement with the throat and guide plate or race way. The magazines are supported in the shiftable rack in such a way that their discharge ends are closer together than their receiving ends and in order to shift said rack it is expedient to first shift the throat and guide plate out of the path of movement of said rack and after the rack has been shifted, again move the throat and face plate back to their operative positions and relations to the appropriate magazine.

Another object of the invention is to provide novel means for counterbalancing and shifting the magazine rack and also means for locking and unlocking said rack so as to maintain the proper relationship between each magazine and the throat and guide plate.

With the above and other objects in view, the invention consists in the novel construction, combination and arrangement of parts, as herein described, illustrated and claimed.

In the accompanying drawings:—Figure 1 is a side elevation of a sufficient portion of

a typographical machine to illustrate the present invention, the magazine rack being shown at the lower limit of its movement. Fig. 2 is a similar view showing the rack elevated. Fig. 3 is a view taken from the opposite side of the machine. Fig. 4 is a fragmentary elevation, illustrating the latch operating mechanism and the means for shifting the guide plate. Fig. 5 is a similar view showing the guide plate shifted out of the path of movement of the rack. Fig. 6 is a fragmentary side elevation showing the means for shifting the throat. Fig. 7 is a similar view showing the throat shifted out of the path of the magazine rack. Fig. 8 is a longitudinal section through one side of the machine on an enlarged scale showing the latch operating mechanism. Fig. 9 is a similar view showing the latch pins withdrawn from the rack frame. Fig. 10 is a fragmentary elevation of the nested rock shafts and the operating means therefor. Fig. 11 is a fragmentary end view of a portion of the rack, showing the means for supporting and adjusting the magazines. Fig. 12 is a detail fragmentary sectional view showing the escapement mechanism for the magazines.

Referring to the drawings A generally designates the frame of the machine and B the magazine rack which comprises the parallel bottom bars 1 the front and rear end or cross bars 2 and 3, respectively, and the oppositely arranged magazine supporting bars 4 which bear a fixed relation to the bars 2 and 3 thus forming a rack frame, the several bars of which bear a fixed relation to each other. Each of the supporting bars 4 is preferably formed of angle iron as indicated in Fig. 11, the bottom flanges 5 thereof forming supports for the magazines indicated at a, b, c, d, e and f. The magazines may be adjusted to properly aline them with the throat C and guide plate or race way D by means of set screws 6 as indicated in Fig. 11.

The magazines are of the usual shape now in common use, being narrower at their discharge ends than at their rear ends, and the bars 4 correspondingly converge toward the front of the machine. This enables the magazines to be slid rearwardly out of engagement with their supporting bars and also held against movement in the opposite direction by said bars.

105

110

The means for shifting the rack will now be described. 7 designates a rack shifting hand lever which may be arranged at either the right or left hand side of the machine, 5 said lever being fast to a tubular rock shaft 8 which is best illustrated in Fig. 10, said rock shaft being journaled in bearings in cross bars 9 of the frame A and being provided with arms 10 at opposite sides of the 10 machine, said arms being connected by turn buckles 11 with the bottom bars 1 of the rack B as shown in Figs. 1, 2 and 3, the turn buckles 11 providing for adjusting the throw of the rack relatively to the raising and lowering arms 10 so as to bring the magazines into proper line with the throat C and guide plate D, when the rack is latched or locked by the means hereinafter described.

The magazines are arranged like the 20 blades of a fan, the forward or discharging ends thereof being arranged closer together than the rear or receiving ends as shown in Figs. 1, 2 and 3. Therefore, in the shifting of the rack, the rear end thereof must move 25 faster than the forward end. In order to accomplish this, I employ a system of levers as follows. A lever 12 is pivotally attached at one end at the point 13 to the frame A. Another lever 14 is pivotally attached at the 30 point 15 to the frame A. The opposite extremities of the levers 12 and 14 are connected by a link 16. To the pivot 17 connecting the adjacent ends of the lever 12 and link 16 there is pivotally attached one end of 35 a link 18 the opposite extremity of which is pivotally attached at 19 to the adjacent bottom bar 1 of the rack. The arrangement of levers and links referred to is duplicated at each side of the machine as will be apparent 40 by comparing Figs. 1 and 2 with Fig. 3. This produces an unequal movement of the front and rear ends of the rack thereby compensating for the unequal distances between the front and rear ends of the magazines. 45

The mechanism for locking and unlocking the rack comprises a rock shaft 20 which is housed or nested within the tubular rock shaft 8 as shown in Fig. 10. On opposite 50 ends of the rock shaft 20 are cams 21 and extending from one of said cams is a pin 22 to which is connected the lower extremity of a cam operating rod 23 which extends upwardly on one side of the rack shifting lever 55 7 where it is connected to a latch 24 the point of which may be thrown into and out of engagement with any one of a series of notches 25 in a curved rack bar 26 secured to the machine frame in fixed position. Connected to 60 the upper extremity of the latch 24 is another rod 27 which is in turn attached to a bell crank lever 28 fulcrumed at 29 on the rack shifting lever 7 above described. The handle ends of both levers 7 and 28 are arranged close together so that both may be

grasped and operated simultaneously as will be apparent from Figs. 1 and 2.

Referring now to Figs. 4 and 5, it will be observed that each cam 21 co-operates with a roller 30 on the lower end of a plunger 31 70 formed with slots 32 to receive guide pins 33 on the machine frame. 34 designates a latch puller in the form of a bar extending along side of the uppermost magazine, said bar being adapted to be shifted lengthwise by 75 means of a pin 35 projecting from the bar 34 and entering an oblique slot 36 in the plunger 31 so that as said plunger 31 is moved by the cam 21, the latch puller 34 will be shifted in one direction. 37 designates a retracting 80 spring for moving the plunger 31 in the opposite direction and maintaining the roller 30 in engagement with the cam 21.

Each of the bars 2 and 3 is provided with a longitudinal series of holes 38 to receive 85 latch pins 39 which pass through holes in the frame A and are pressed inwardly by means of latch springs 40 as best illustrated in Figs. 8 and 9. Each latch puller 34 is provided with a plurality of wedge or cam faces 90 41 which operate against the heads 42 of the latch pins 39 so as to draw said pins 39 out of holes 38 when said latch puller is moved endwise in one direction by the mechanism 95 previously described. This effects an unlocking of the rack so that it may be subsequently elevated or depressed by the rack shifting lever 7. The latch puller 34 also operates to shift the throat C out of the path of the rack and magazines, the end of the 100 puller bar 34 being concaved or notched as shown at 43 in Figs. 6 and 7 to engage a pin or stud 44 on the adjacent side of the throat C. Therefore, when the puller bar 34 is operated by the plunger 31 and cam 21, the 105 throat C is swung outwardly on its pivotal connection at the point 44' with an extension 45 of the machine frame A until it assumes the position illustrated in Fig. 7, said throat being restored to its working position by 110 means of the retracting spring 46.

Simultaneously with the shifting movement of the throat C, the guide plate or race way D is also shifted out of the path of the 115 rack frame and mechanism by the means best illustrated in Figs. 4 and 5 wherein it will be observed that the guide plate D is provided with an arm 47 having guide slots 48 which receive guide pins 49 on the frame A. The arm 47 has a pin 50 extending laterally therefrom through an oblique slot 51 in the plunger 31 and therefore when the plunger 31 is thrust upwardly by the cam 21 to unlatch the rack frame, the arm 47 is operated upon by said plunger to shift the 120 guide plate or race way D from its operative position shown in Fig. 4 to its inoperative position shown in Fig. 5.

In Fig. 12 I have illustrated the escape- 125 ment mechanism for the matrices, 52 design- 130

nating one of the run ways of a magazine and 53 matrices therein. 54 designates an escapement lever which is held in one position by means of a spring 55. The escapement lever is provided with a lip 56 at one end which is engaged by a corresponding lip on a trip 57 which is adapted to be operated by one of a series of trip rods 58 at the front of the machine, said trip rods 58 being operated in the usual manner. A bank of escapements is employed at the discharge end of each magazine, said escapements being raised and lowered with their respective magazines. The trip rods 58 pass through 15 guide openings in a cross bar 59 connecting the arms 47 above referred to so that the upper extremities of said rods 58 are shifted out of the way simultaneously with the guide plate or race way D as shown by comparison of Figs. 4 and 5. The arms 47 are drawn inwardly by the retracting springs 60.

The rear end of the magazine rack is controlled directly by the bottom bars 1 of the rack which are in turn controlled by the lifting arms 10. The front end of the rack is controlled by links 61 which are pivotally connected at 62 to the front end or cross bars 2 of the rack, the links 61 being pivotally connected at 63 to the extremities of the levers 14 at the points 64.

65 designates counterbalancing springs connected at one end to the rack at the point 66 and at the opposite end at 67 to extensions or arms 68 of the frame A. E designates the usual distributor arranged above the throat C so as to discharge into the same.

From the foregoing description taken in connection with the accompanying drawings it will now be understood that when the operator desires to shift the rack so as to bring any particular magazine into line with the throat and guide plate or race way, he grasps the lever 7 and at the same time he grasps the lever 28. He first operates the lever 28 to withdraw the latch pins 39 and shift the throat C and guide plate D out of the way. He then moves the lever 7 until the desired magazine is in its proper place. Thereupon he releases the lever 28 which 50 serves by means of the latch 24 to lock said lever and also to release the latch pins 39 permitting them to enter the proper holes 38 in the bars 2 and 3 of the rack. Simultaneously therewith the throat C and guide 55 plate or race way D are restored to their operative positions. Any variation between the holding position of the latch 24 and the holding positions of the latch pins 39 may be compensated for by adjusting the turn buckle 11 above referred to. The magazines are usually wider at their receiving ends than at their discharge ends, imparting thereto a wedge shape, and accordingly the rack frame is of the same general shape in 60 plan, the supporting bars 4 converging from

their rear toward their front extremities. This facilitates the removal and replacement of the magazines.

It will of course be understood that the rack may be made of any desired size and 70 capacity according to the number of magazines to be used therein and that various changes in the form, proportion and minor details of construction may be resorted to without departing from the principle or sacrificing any of the advantages of the invention.

What I claim is:—

1. In a typographical machine, the combination of a plurality of removable magazines, a multiple magazine rack on which the magazines are supported so that their discharge ends are at less distance apart than their receiving ends, and manually controlled means for unequally raising and lowering the front and rear of said rack. 80

2. In a typographical machine, the combination of a plurality of removable magazines, a multiple magazine rack on which the magazines are supported so that their discharge ends are at less distance apart than their receiving ends, manually controlled means for unequally raising and lowering the front and rear of said rack, and counterbalancing means for said rack. 90

3. In a typographical machine, the combination of a plurality of removable magazines, a multiple magazine rack on which the magazines are supported so that their discharge ends are at less distance apart than their receiving ends, manually controlled means for unequally raising and lowering the front and rear of said rack, and means for locking and unlocking said rack. 100

4. In a typographical machine, the combination of a plurality of removable magazines, a multiple magazine rack on which the magazines are supported so that their discharge ends are at less distance apart than their receiving ends, latches for locking said rack, a manually operable lever and connections for shifting said rack up and down, and other connections associated with said lever for operating said latches. 105

5. In a typographical machine, the combination of a plurality of removable magazines, a multiple magazine rack on which the magazines are supported so that their discharge ends are at less distance apart than their receiving ends, a guide plate, manually controlled means for shifting said rack, and means for shifting said guide plate out of the path of said magazine rack. 115

6. In a typographical machine, the combination of a plurality of removable magazines, a multiple magazine rack on which the magazines are supported so that their discharge ends are at less distance apart than their receiving ends, a throat, manually controlled means for shifting said rack, and 120 125 130

means for shifting said throat out of the path of said magazine rack.

7. In a typographical machine, the combination of a plurality of removable magazines, a multiple magazine rack on which the magazines are supported so that their discharge ends are at less distance apart than their receiving ends, manually controlled means for unequally raising and lowering the front and rear of said rack, and means for adjusting the throw of said rack in relation to the rack shifting lever.

8. In a typographical machine, the combination of a plurality of removable magazines, a multiple magazine rack on which the magazines are supported so that their discharge ends are at less distance apart than

their receiving ends, latches at opposite sides of said rack for locking the latter, a pair of nested rock shafts, latch operating connections between said latches and one of said rock shafts, raising and lowering connections between said rack and the other rock shaft, a magazine rack shifting lever on one of said rock shafts, and means on said lever for operating said latch operating connections. 20 25

In testimony whereof I affix my signature in presence of two witnesses.

JOHN W. GRAHAM.
